UNITED STATES PATENT OFFICE.

FERDINAND ANTOINE SCHMOUTZ, OF PARIS, FRANCE.

KNIGHT ENGINE.

1,316,867.

Specification of Letters Patent. Patented Sept. 23, 1919.

Application filed October 22, 1917. Serial No. 197,819.

To all whom it may concern:

Be it known that I, FERDINAND ANTOINE SCHMOUTZ, citizen of the Republic of France, residing at 3 Rue Boucicaut, Paris, 5 in the Republic of France, have invented new and useful Improvements in Knight Engines, of which the following is a specification.

The Knight engine is coming into extensive use in the automobile industry on account of its silent working, its flexibility, its efficiency and its stability. In spite of the recognized qualities which this motor possesses at the present time, it may be 15 modified in an important measure as concerns the adjustment of the compression, this being done in such manner that the motor can be readily started by the hand crank, and on the other hand it will allow 20 of using a very high rate of compression while running and at the same time the rate of compression can be modified as desired, according to the amount of power which the engine is called upon to furnish. 25 In motors of the valve type, the compression is diminished at the time of starting by sending into the muffler box a part of the fresh gas drawn in, and the power of the engine is regulated by modifying the 30 quality of the gas mixture supplied to the engine, this being done by acting on the throttle valve of the carburetor. As will be observed, the means employed for starting and operating the engine are not of a 35 very economical nature.

The improvement made in the Knight engine by the present invention consists essentially in regulating the compression by varying the size of the gas inlet openings, 40 without acting on the openings of the exhaust or upon the carburetor. In this way the compression can be modified gradually throughout a very wide range which starts with very low values corresponding 45 to starting and slowing up of the engine, and rises to the highest values allowing the use of low quality of producer gas. The gas mixture drawn into the engine will now have an invariable quality, and only 50 its quantity will be variable, and in no case there will never be any loss of gas.

These results are obtained in the following manner:

A. By dividing the outer bushing or 55 sleeve of the Knight engine according to

two diametrically opposite generatrices so as to form two half-bushings, one corresponding to the inlet and the other to the exhaust.

B. By operating the inlet half-bushing 60 independent of the exhaust half-bushing.

C. Lastly, by providing the inlet half bushing with a set of regulating levers which allow of varying the position of this half-bushing with reference to the inner 65 bushing containing the piston, and with reference to the exhaust half-bushing.

The displacement of the exterior inlet half-bushing with reference to the inner bushing allows of varying gradually and 70 as desired the size of the gas inlet openings and accordingly the amount of cylinder contents, upon which depend the compression and the power. Since the exhaust half-bushing is not operated, the size of the 75 exhaust openings remains the same.

Any suitable arrangement can be employed to effect the operation of the inner bushing and the two outer half-bushings.

In the engine designed according to this 80 invention and represented in constructive example in the accompanying drawings, this operation is effected in an especially simple manner by the use of a solid cylinder operated by the engine and provided with 85 three suitable profile grooves or traveling ways, each of which is adapted to work together with a stud (or roller) which is displaced within said traveling ways, the studs or rollers being connected with the 90 inner bushing or with one or the other of the outer half-bushings.

In these drawings:

Figure 1 is a vertical section of a Knight engine improved according to the present 95 invention, the section being made along the broken line 1—1 of Fig. 2.

Fig. 2 is a horizontal section of the engine taken approximately along the broken line 2—2 of Fig. 1, some parts being shown in 100 elevation. In this figure the motor is supposed to contain a set of two cylinders.

Figs. 3 to 6 are diagrams showing the position of the bushings at 4 points of the cycle.

As will be observed in Figs. 1 and 2, the engine designed according to the present invention uses the following parts of the Knight engine, namely, the cylinder 1, cylinder head 2 and inner bushing 3 in which 110

the piston 4 moves. The outer bushing is cut according to two diametrically opposite generatrices so as to form two half-bushings 5 and 6, of which the first corresponds to the inlet and the second to the exhaust.

Gas inlet takes place through the openings 7 of the cylinder 8 of the half-bushing 5 and 9 of the inner bushing, when these openings come opposite each other. In the same way, 10 the exhaust takes place by the juxtaposition of the openings 10 of the inner bushing 3, 11 of the half-bushing 6, and 12 of the cylinder.

The openings are brought in line at the 15 required moment, by the relative displacement of the inner bushing and the two outer half-bushings, these three parts being independent of each other and designed to be operated for instance by the use of a distributor 20 made up of a cylinder 13 provided with the sliding ways 14, 15 and 16 and operated by the shaft 17 and pinions 17^a and 17^b at a speed equal to half the engine speed.

The bushing 3 and the two half-bushings 25 5 and 6 are respectively solid with the studs 18, 19 and 20 applied upon the sliding ways 14, 15 and 16 so as to produce the linear and alternative displacement of the bushings, on the rotation of the distributor 13.

30 It will be observed that the stud 19 is not attached directly to the half-bushing 5, as is the case for the stud 18 and bushing 3 on one hand, and stud 20 and half-bushing 6 on the other. This stud 19 is carried on the lever 21 to which is articulated at 22 a strap 23 which is also connected to the lug 24 of the half-bushing 5. The lever 21 carries a shaft 25 journaled in a collar 26 cast on the end of one arm of a bent lever 27 articulated 35 on a fixed shaft 28 and connected by a strap 29 to a second bent lever 30 articulated on a fixed shaft 31 and employed for operating the mechanism.

When the bent lever 30 is moved in one 40 direction or the other, the lever 27 turns about its shaft 28 and the collar 26 rises or falls and thus carries with it the shaft 25 and consequently the lever 21 and the half-bushing. In the diagram, Fig. 3, the full 45 lines represent one position of the levers, and the dotted lines another position of this system of levers after the operating lever 30 has swung toward the left, and this latter movement causes the half-bushing 5 to descend with reference to the half-bushing 6 and the inner bushing 3.

It follows from the above that by operating the lever 30, the half-bushing 5 can be displaced with reference to the half-bushing 50 6 and the bushing 3, in a continuous manner, in the proper direction, and by any desired amount.

It is thus evident that this allows of a 55 gradual adjustment of the size of the inlet openings from zero up to the maximum

corresponding to a perfect alignment of the openings 7, 8 and 9.

By working the lever 30, the driver can thus adjust at will the amount of gas in the cylinder and accordingly the value of the 70 compression and of the power, without loss of gas and without any action on the carburetor, and this latter will always supply a constant quality of gas mixture.

Figs. 3 and 5 represent the positions of 75 the bushings corresponding to four points of the cycle and these figures allow of observing the effect produced by a displacement of the half-bushing 5 upon the opening of the inlet orifices. It will be seen that the present 80 engine possesses the advantages of the Knight engine as regards the gas inlet and exhaust, lubrication, simple construction and solidity.

The operating lever system and the distributor 85 13 are here shown by way of example and can be modified without departing from the principle of the invention. However it should be remarked that this distributor is specially advantageous, and in 90 the case of a two-cylinder engine such as shown in Fig. 2, it allows of operating the bushings of the two cylinders.

Having now described my invention, what I claim as new and desire to secure by Letters Patent is:

1. In an explosion engine, the combination of a working cylinder having inlet and exhaust openings, segmental inlet and exhaust valves movable in said cylinder and having inlet and exhaust openings, respectively, a bushing movable within the said segmental valves and having inlet and exhaust openings, driving means for reciprocating the segmental valves and the bushing and means for varying the position of one of the segmental valves with respect to the driving means.

2. In an explosion engine, the combination of a working cylinder having inlet and exhaust openings, segmental inlet and exhaust valves movable in said cylinder and having inlet and exhaust openings, respectively, a bushing movable within the said segmental valves and having inlet and exhaust openings, driving means for reciprocating the segmental valves and the bushing and means for varying the position of the inlet segmental valve with respect to the driving means.

3. A distribution system for Knight engines, containing, in combination, a cylinder, inlet and exhaust openings disposed in said cylinder, a half-bushing for inlet and a half-bushing for exhaust movable in said cylinder and juxtaposed according to two diametrically opposite generatrices, inlet and exhaust openings disposed in these two half-bushings, a bushing movable within the said half-bushings, inlet and exhaust openings,

disposed in said bushing, a straight lever, means for connecting one end of this straight lever to the outer half-bushing used for inlet, a bent lever pivoted about a fixed shaft 5 and having one arm articulated upon the straight lever, means for operating the bent lever, means acting upon the free end of said straight lever and producing a to-and-fro movement of the outer half-bushing used 10 for inlet, and means for producing independent to-and-fro movements of the outer half-bushing used for exhaust and of the inner bushing, substantially as described and for the purpose set forth.

15 4. A distribution system for Knight engines, containing, in combination, a cylinder, inlet and exhaust openings disposed in said cylinder, a half-bushing for inlet and a half-bushing for exhaust movable in said 20 cylinder and juxtaposed according to two diametrically opposite generatrices, inlet and exhaust openings disposed in these two half-bushings, a bushing movable within the said half-bushings, inlet and exhaust openings 25 disposed in said bushing, a straight lever, a lug cast with the outer half-bushing used for inlet, a strap connecting one end of the straight lever to said lug, a bent lever pivoted about a fixed shaft and having one arm 30 articulated upon the straight lever, a second bent lever, a strap connecting one arm of this bent lever to the free arm of the first bent lever, a stud disposed at the free end of the above mentioned straight lever, two 35 lugs one of which is disposed on outer half-bushing used for exhaust and the other on the inner bushing, a stud carried by each of these lugs, a cylinder, three grooves or sliding ways disposed on said cylinder, with 40 one of the three above-mentioned studs working in one of the grooves respectively, and means for rotating this cylinder upon its axis, substantially as described and for the purpose set forth.

45 5. In an explosion engine, the combination of two working cylinders arranged in parallelism to each other and having both inlet and exhaust openings, segmental inlet

and exhaust valves movable in each of said cylinders and having inlet and exhaust openings, respectively, a bushing movable in each of the pairs of segmental valves and having inlet and exhaust openings and driving means for reciprocating the four segmental valves and the two bushings in the two cylinders, said driving means embodying one rotatable member having three cam grooves on its outer periphery and means for rotating said member. 50

6. In an explosion engine, the combination of two working cylinders arranged in parallelism to each other each of them having inlet and exhaust ports, segmental inlet and exhaust valves movable in each of said cylinders and having inlet and exhaust 55 openings respectively, a bushing movable within each of the pairs of segmental valves and having inlet and exhaust openings, driving means for reciprocating the four segmental valves and the two bushings in the 60 two cylinders, said driving means embodying one rotatable member having three cam grooves in its outer periphery, means for rotating said member, studs on the bushings in both cylinders engaging in one cam 65 groove, studs on the exhaust segmental valves in both cylinders engaging in the second cam groove, two studs engaging in the third cam groove, two pivoted levers 70 upon which said studs are carried respectively, means for connecting the said levers to the inlet segmental valves of the two cylinders, respectively, one shaft upon which both of said levers are pivoted and means 75 connected to said shaft for varying the position of the levers and inlet segmental valves, substantially as described and for the purpose set forth. 80

In testimony whereof I have signed my name to this specification in the presence of 85 two subscribing witnesses.
